UNITED STATES PATENT OFFICE.

STUART W. CRAMER, OF CHARLOTTE, NORTH CAROLINA.

AIR-CONDITIONING APPARATUS.

1,073,095.

Specification of Letters Patent. Patented Sept. 16, 1913.

Application filed April 15, 1909. Serial No. 490,079.

To all whom it may concern:

Be it known that I, STUART W. CRAMER, a citizen of the United States, residing at Charlotte, in the county of Mecklenburg and 5 State of North Carolina, have invented certain new and useful Improvements in Air-Conditioning Apparatus; and I do hereby declare the following to be a full, clear, and exact description of the invention, such as will enable others skilled in the art to which it appertains to make and use the same.

This invention relates to apparatus for treating air, whereby the air is cleansed of 15 its impurities, and is conditioned by the addition or subtraction of moisture and heat as may be desired.

The object of the invention is to provide an apparatus along new and novel lines, 20 whereby air-cleansing, moistening, heating and cooling are attained as heretofore in similar types of apparatus, with the further advantage that cooling may also be continued even though moistening be discontinued, and without the aid of refrigeration, the circulation of cold water, or other liquids, and the like.

By way of definition, it is not amiss to point out that in the recent rapid evolution 30 of the art of air conditioning, that two types have been developed, viz; one, which may be termed the central station type, with ducts leading to different parts of a building; and the other, individual spray head 35 types, a number of which are uniformly distributed throughout the rooms in the building.

My invention relates to both of these types of apparatus.

40 The former type of apparatus is also frequently referred to as a "fan and heater" system for heating and ventilation; in that form, however, nothing is claimed for it in the way of a cooling or moistening apparatus; when these features are added it very properly becomes an air conditioning apparatus.

It is well known that in this or any other 50 type of humidifier, air can be cooled in direct proportion to the amount of moisture evaporated, the limit of which is, of course, saturation. Advantage is taken of this fact, to cool the air required for ventilation by saturating it before introduction into a 55 building, so that in summer time it may be

cooled to the wet bulb temperature of the air passing through the apparatus. That this exerts a very decided and beneficial cooling effect, is not to be denied, a great deal of the time; its only drawback lies in 60 the fact that a great many times by continuing to saturate the air and introduce it into the building, the already disagreeable humidity may be materially increased. At such times the moisture must be cut off, 65 and then no cooling effect is obtainable except so far as is the difference between the air passing through the apparatus and that in the room to be cooled. The air entering the apparatus is sometimes entirely outside 70 air, at other times it is all inside air, and at other times still it is a mixture of the two, the inside and the outside air. Considering, therefore, that in all cases where comfort alone is the desideratum, some humidity is 75 very desirable but only moderate in amount, and excessive humidity is exceedingly objectionable, it becomes evident that only a limited amount of cooling by evaporation is permissible as it is ordinarily accomplished. 80

One of the chief points of novelty and merit of this invention lies in the fact that cooling by evaporation can still be continued and yet the moisture be shut off. The advantage thereby derived is made clear by 85 the following hypothetical case: Consider a warm day outside with a temperature of 80 degrees F. and 50% relative humidity, at which each cubic foot of air contains 5.47 grains of moisture. Saturating that air 90 and introducing it into a building in which the temperature is also 80 degrees produces a cooling effect of 13 degrees; that is to say all the air that is introduced under such circumstances has been cooled to 67 degrees 95 F. and contains 7.24 grains of moisture per cubic foot. The introduction of this additional moisture required to saturate the air, however, causes the relative humidity in the room to increase very rapidly. If the temperature of the room still remains at 80 degrees in spite of the cooling effect, the additional moisture added causes the relative humidity to very soon become about 66%. If the room is cooled down to a temperature of 105 75 degrees the moistening effect is still worse, because the relative humidity then will approximate 75%. No one would think of maintaining over 50% humidity under such circumstances if it could be helped; 110

therefore, if that cooling effect of 13 degrees could be utilized as a cooling effect alone without the addition of moisture, an ideal condition would result. Such is the function of the apparatus covered by my invention.

The invention will be fully disclosed in the following specification and claims.

In the accompanying drawings, which 10 form part of this specification: Figure 1 represents a plan view partly in horizontal section, of apparatus embodying my invention. Fig. 2 represents a vertical transverse section through the spray chamber on line 2—2, Fig. 1, showing the cold air tubes and the cooling chamber beyond. Fig. 3 15 represents a vertical longitudinal section on line 3—3 Fig. 1, and Fig. 4 represents a sectional plan view of the baffle plates on 20 an enlarged scale.

Reference being had to the drawings and the designating characters thereon, the numeral 1 indicates an outer casing or shell, which may be built of sheet metal, brick or 25 other preferred material and constitutes an air chamber; 2 a spray or air moistening chamber and 3 a cooling chamber within the air chamber.

4 is the air inlet to the spray chamber, 5 30 the air inlet to the cooling chamber, and 6 are heating coils for tempering the incoming air to each chamber as may be desired.

7 are spray heads within the spray chamber, and 8 are tubes arranged within the cooling chamber and through which passes the incoming air to be cooled. Within the cooling chamber 3 the tubes 8 are arranged 40 so that the air entering the spray chamber passes through the cooling chamber, around, over and above the tubes 8 and thence out to the fan inlet or otherwise.

9 are baffle plates or condensing bodies for collecting the surplus moisture from the 45 spray laden incoming atmosphere. The baffle plates 9 are of sheet metal substantially V-shaped and are suitably fastened at their ends in trough like members, and are properly spaced by side plates 92 provided with 50 notches which engage the edges of the plates, as shown in Fig. 4, and the trough like members are secured together by the rods 94, only one of which is shown. The bank of baffle plates is properly secured within the 55 casing in any preferred manner.

In Figs. 1, 2 and 3 10 is the outlet for the spray charged air after it has passed through the cooling chamber, thence into the fan 11, which may be of any preferred type. 60 12 is a chamber to receive the cooled air which has passed through the tubes 8 in the cooling chamber, from whence it passes through the fan 13. 14 are dampers separating the spray chamber 2 from the outlet 65 12. 15 is a damper separating the outlets

from the two fans 11 and 13, and 16 is a damper controlling the supplemental outlet 17 to the fan 11.

From the foregoing it will be seen, that one current of air enters the spray chamber 70 2 through the inlet 4, then passes around and above the tubes 8 in the cooling chamber 3 on its way out of the apparatus through the opening 10 leading to the fan 11; from whence it travels in the direction 75 indicated by the arrows, either mixing with the air from the other fan 13 and entering the building through outlet 17, or from whence by closing the damper 15 and opening the damper 16 the air from the fan 11 80 can be directed out through its auxiliary outlet 17' to the outer atmosphere. The air entering the inlet 5 to the cooling chamber 3 passes through the tubes 8 which are kept cooled by the spray and air from the 85 spray chamber, thence through the chamber 12 into the fan 13 and out as indicated by the arrows through the main outlet 17 into the building. So that, with this apparatus there are two separate and distinct currents, one of them cooled to the 90 temperature of saturation, which is the wet bulb temperature of the air passing through the spray and to which moisture has been added; and the other, air cooled to nearly 95 the same temperature, but to which no moisture whatever has been added.

By suitably adjusting the parts, both currents of air passing through the apparatus can be cooled to approximately saturation 100 temperature and directed into the building from both fans, thereby producing maximum cooling and moistening effects. In the matter of regulation of the amount of moisture in the building that is being served, when the humidity has reached the point at 105 which it is desired to maintain it, or at least not to exceed it, dampers 14 and 15 are closed, and damper 16 is opened; under these conditions the dry cooled current of 110 air coming through the fan is delivered into the building without the addition of any more moisture, and the other current of cooled and saturated air from the fan 11 is directed out through its auxiliary or supplemental outlet 17' into the outer atmosphere. When the humidity has again 115 dropped to the point that it is permissible to introduce more moisture into the room, dampers 14 and 15 are opened and damper 120 16 is closed, and then both fans 11 and 13 deliver into the building again through outlet 17.

Further elucidation is deemed unnecessary, as the foregoing description with the 125 accompanying drawings will suggest to any one skilled in the art to which my invention appertains some of the various modifications of which the invention is susceptible.

It is obvious that in lieu of the spray 130

heads shown, other devices may be employed for cooling by the evaporation of the moisture; and that changes in form and arrangement may be made without departing 5 from the spirit of my invention.

Having thus fully described my invention, what I claim is

1. In an air conditioning apparatus, means for producing a current of air, means 10 for cooling said current of air, said means being exposed to an auxiliary current of air cooled by the evaporation of moisture, and means for commingling or separating the two currents of air.
- 15 2. In an air conditioning apparatus, a fan, an air chamber, a spray chamber, a plurality of exits for the moistened air in the spray chamber, a commingling chamber to mix the air from the air chamber and the moistened air in the spray chamber, and means for controlling the rate of mixture.
- 20 3. In an air conditioning apparatus, a spray chamber, spray heads within said chamber, a cooling chamber containing tubes over which pass the air from the spray chamber, a fan having connection with said chambers, a commingling chamber for mixing the air from said air and spray chambers, and means for controlling the moistened air issuing from the spray chamber.
- 25 4. In an air conditioning apparatus, a spray chamber, spray heads within said chamber, a cooling chamber containing tubes, over which pass air from the spray chamber, fans for supplying air to said chambers, a commingling chamber for mixing the air from said air and spray chambers, and means for controlling the moistened air issuing from the spray chamber.
- 30 5. In an air conditioning apparatus,

means for producing a current of air, an air chamber, a spray chamber, a cooling chamber containing tubes, an exit from the spray chamber provided with controlling means, a separate exit from the spray chamber through the cooling chamber and around 45 said tubes, and a chamber in which the air from the spray chamber and the cooling chamber are commingled.

6. In an air conditioning apparatus, an air chamber, a spray chamber, spray heads within the spray chamber, a fan for supplying air to said spray chamber, a fan for supplying air to said air chamber, and means for commingling and separating the moistened air issuing from the spray chamber and the air issuing from the air chamber.

7. In an air conditioning apparatus, a spray chamber, spray heads within said spray chamber, an air cooling chamber influenced by air from said spray chamber, a fan having connection with the spray chamber, a fan having connection with the air cooling chamber, and means for controlling the supply of air from said fans.

8. In an air conditioning apparatus, an air chamber, a spray chamber within said air chamber, spray heads within the spray chamber, a fan for supplying air to said spray chamber, a fan for supplying air to said air chamber, and means for commingling or separating the moistened air issuing from the spray chamber and the air issuing from the air chamber.

In testimony whereof I affix my signature, in presence of two witnesses.

STUART W. CRAMER.
